(57) **CLAIM**

The ornamental design for an automated teller machine surround, as shown and described.

DESCRIPTION

FIG. 1 is a front elevation view of an automated teller machine surround showing our new design, shown in a used condition; FIG. 2 is a left side view thereof, shown in a used condition; FIG. 3 is a front perspective view thereof, shown in an unused condition;

FIG. 4 is a front elevation view thereof;

FIG. 5 is a back elevation view thereof;

FIG. 6 is a top plan view thereof;

FIG. 7 is a bottom plan view thereof;

FIG. 8 is a left side elevation view thereof; and,

FIG. 9 is a right side elevation view thereof.

The broken lines in the drawings represent environmental structure and form no part of the claimed design.

1 Claim, 9 Drawing Sheets
